[57] CLAIM

The ornamental design for a tool rest for milling planer, as shown and described.

DESCRIPTION

FIG. 1 is a perspective view of a tool rest for milling planer showing my new design;

FIG. 2 is a top plan view;

FIG. 3 is a right side elevational view;

FIG. 4 is a rear elevational view;

FIG. 5 is a left side elevational view;

FIG. 6 is a front elevational view; and,

FIG. 7 is a bottom plan view thereof.

FIG. 1 has been drawn on an enlarged scale with respect to FIGS. 2-7.
